(57) **CLAIM**

The ornamental design for a tire, as shown and described.

DESCRIPTION

FIG. 1 is a perspective view of a tire showing my new design; FIG. 2 is a front view thereof, the top and bottom views being identical thereto, the rear view being a mirror image thereof; FIG. 3 is a right side view thereof;

FIG. 4 is a left side view thereof; and,

FIG. 5 is an enlargement of the tread design in the region indicated by lines A and B in FIG. 2.

The dashed broken lines illustrate unclaimed environmental structure; the dot-dash broken lines in FIGS. 1-4 represent an unclaimed boundary; the dot-dash broken lines in FIG. 5 identify an area of enlargement; the broken lines themselves form no part of the claimed design.
